(57) CLAIM

The ornamental design for an animal toilet, as shown and described.

DESCRIPTION

FIG. 1 is a perspective view of an animal toilet of my new design;

FIG. 2 is a right side of the animal toilet shown in FIG. 1; FIG. 3 is a left side view of the animal toilet shown in FIG. 1;

FIG. 4 is a front view of the animal toilet shown in FIG. 1; FIG. 5 is a rear side view of the animal toilet shown in FIG. 1;

FIG. 6 is a top view of the animal toilet shown in FIG. 1; and,

FIG. 7 is a bottom view of the animal toilet shown in FIG. 1.

The broken lines illustrate portions of the animal toilet that form no part of the claimed design.

1 Claim, 7 Drawing Sheets
